UNITED STATES PATENT OFFICE.

JOHN HENRY HORSTMAN, OF CINCINNATI, OHIO.

TUFTING-FRAME.

SPECIFICATION forming part of Letters Patent No. 729,588, dated June 2, 1903.

Application filed October 24, 1902. Serial No. 123,523. (No model.)

To all whom it may concern:

Be it known that I, JOHN HENRY HORSTMAN, a citizen of the United States of America, and a resident of Cincinnati, county of Hamilton, State of Ohio, have invented certain new and useful Improvements in Tufting-Frames, of which the following is a specification.

The object of my invention is a tufting-frame in which the prods for passing through the burlap and cover may be readily adjusted longitudinally and transversely for use with tufts of different styles and sizes and which has a novel means for securing the tufting-button in place. This object is attained by the means described in the specification and illustrated in the accompanying drawings, in which—

Figure 1 is a plan view of a tufting-frame embodying my invention, the right-hand end of the frame being shown with a piece of burlap over it, the center of the frame showing the burlap removed to expose the transverse bars and the tufting-prods mounted thereon, and the left-hand end of the frame showing the swinging side pieces broken away. Fig. 2 is a transverse sectional view of the same upon an enlarged scale. Fig. 3 is a detail plan view of one end of a transverse bar, showing two of the tufting-prods mounted thereon, upon an enlarged scale, with the swinging arms journaled thereon. Fig. 4 is a detail side elevation of the same, one of the tufting-prods and the swinging arm mounted thereon for bending prongs of the tufting-button being shown in elevation and the other being shown in section. Fig. 5 is a detail elevation of one of the tufting-prods and the swinging arm, taken at a right angle to the view shown in Fig. 4. Fig. 6 is a detail view of the same, taken in the same position as that shown in Fig. 4, the full line showing the position of the swinging member before the prongs are bent and the dotted line showing its position in the course of the operation. Fig. 7 is a detail view showing the tuft, the button, and the washer in the positions they occupy when the operation is complete.

Referring to the parts, the tufting-frame consists of end members a a' and side members a^2 a^3 . Members a^2 and a^3 have a series

of longitudinal perforations a^4 to receive pins b b' , which project downward from the ends of transverse bars B . These perforations are placed at distances apart such that the transverse bars may be secured in place at any desired distance apart, according to the style and size of the tuft to be formed. Upon bars B are mounted a series of adjustable tufting-prods C . End members a a' are sealed off, so that the prods C may be adjusted to the positions upon the transverse bars B , desired for the particular form of tuft being made. Upon side members a^2 a^3 are hinged strips a^5 a^6 , which are turned down upon ends of transverse bars B after they have been adjusted to hold them more firmly in place, as shown in Fig. 1.

Transverse bars B consist of parallel rods b^2 b^3 , connected at their ends by a block b^4 , from which the pins b and b' project.

Each of prods C consists of a flat vertical stud c , having lateral fingers c' c^2 , which engage rods b^2 b^3 snugly, so as to allow the prods to be pushed along the rods to any desired position and to hold themselves in place with a yielding pressure. Between fingers c' c^2 and beneath stud c is secured a horizontal journal-pin c^3 , upon which a swinging arm c^4 is journaled. Arm c^4 has upon each side two guide-wings c^5 c^6 . Arm c^4 is capable of a revolution about pin c^3 through an angle of one hundred and eighty degrees.

In operation after tufting-prods C have been adjusted to the positions desired for the style of tuft, the position shown in Fig. 1 being that used for diamond tufts, washers D are placed over each stud c , burlap e is placed over the frame and is pushed down, so that the prods C project up through it. The frame has horizontal pins a^8 upon each side upon which the burlap is caught. Stay-rods F are then placed over the burlap and pushed through perforations a^7 in the sides a^2 a^3 to hold the burlap in place, this being the only function of the rods F , and the same being removed after the operation is complete by simply pulling them out through the perforations a^7 . The burlap being in place, cover e' , which has preferably been previously pierced at the requisite intervals with holes to receive the studs c , is placed upon the burlap, studs c

projecting up through the cover. Tufting-buttons G are then placed upon top of studs c, the prongs g and g' passing downward upon each side of the stud through the cover e', the burlap e, and the washers D downward upon each side of the arm c'. The workman then holds the button downward upon the stud from above and reaching beneath the frame pulls swinging arm first in one direction, which bends one of the prongs upward against the washer, and then pushes it in the other direction, which bends the other prong upward. After the tufts have been stuffed and the buttons inserted in place and bent, as thus described, the rods F being removed, the cushion may be readily removed from the frame, as the prongs and washers pass freely upward clear of the studs c, by an upward pull.

20 What I claim is—

1. In a tufting-frame the combination of a frame, transverse bars adjustable longitudinally upon the frame, flat tufting-prods adapted to project up through the cover and to enter between and to act as a guide for the prongs of the button in their passage through the goods and washer, said prods being mounted upon and adjustable along the transverse bars.
2. The combination of a frame, transverse bars adjustable longitudinally upon the frame, each transverse bar consisting of two parallel rods, flat tufting-prods adapted to project up through the cover and to enter between and act as a guide for the prongs of the button in their passage through the goods and washers, said prods having fingers to engage the rods and to adapt them to slide transversely upon the rods to be adjusted to dif-

ferent positions, substantially as shown and 40 described.

3. The combination of a frame, transverse bars mounted upon the frame, tufting-prods mounted upon the bars and swinging arms mounted beneath the prods for bending the 45 prongs of tufting-buttons substantially as shown and described.

4. A tufting-frame, transverse bars mounted upon the frame consisting of two parallel rods, tufting-prods mounted between the 50 rods, a journal-pin secured between the rods beneath the tufting-prod, and a swinging arm journaled upon the pin for bending the prongs of tufting-buttons substantially as shown and described.

5. A tufting-frame, transverse bars mounted upon the frame consisting of two parallel rods, tufting-prods each consisting of a stud with lateral fingers for adjustably engaging the rods, a pin mounted between the fingers 60 beneath the stud, and a swinging arm journaled upon the pin for bending the prongs of tufting-buttons substantially as shown and described.

6. A tufting-frame having in its side members a series of perforations, transverse bars having at their ends downwardly-projecting pins to engage the perforations for adjusting the rods, strips hinged to the side members to be turned down upon the ends of the transverse bars, tufting-prods mounted adjustably upon the transverse bars substantially as shown and described.

JOHN HENRY HORSTMAN.
